UNITED STATES PATENT OFFICE.

JOSEPH PODJEVIN, OF SCHENECTADY, NEW YORK.

MOVING-PICTURE MACHINE.

1,350,388.

Specification of Letters Patent. Patented Aug. 24, 1920.

Application filed January 14, 1915. Serial No. 2,116.

To all whom it may concern:

Be it known that I, JOSEPH PODJEVIN, a citizen of the United States, residing at Schenectady, county of Schenectady, State of New York, have invented certain new and useful Improvements in Moving-Picture Machines, of which the following is a specification.

My invention relates to apparatus for taking and projecting moving pictures, and more particularly to moving picture cameras and projectors.

The object of my invention is to provide a combined camera and projector which is especially suitable for use in the home, is compact, easily portable, and so simple in construction and so nearly automatic in operation that it can be used by unskilled persons or amateurs to take and project moving pictures. A further object is to provide a projector which will without stopping or changes of any kind repeat the exhibition of the pictures as often as desired and will always exhibit them in the same order as they were taken. Another object is to provide means whereby the camera can be loaded and unloaded in daylight as easily as a hand camera of the usual type. Still another object is to improve moving picture and photographic apparatus in general so as to facilitate and improve both the taking and projecting of pictures, as will be hereinafter pointed out with greater particularity.

In carrying out my invention I use as a picture vehicle or picture bearing element a plate of glass or other non-inflammable transparent material instead of the inflammable film commonly employed. The pictures are printed or mounted on this plate in such a way that as the plate is moved by the driving mechanism the pictures are presented on the screen in proper sequence. In the preferred arrangement the pictures are so arranged on the plate that they can be shown over and over again in the order in which they were taken and as long as desired, without stopping either the driving mechanism or the movement of the plate. I prefer to arrange the pictures in an endless row or series in which each picture is at a uniform distance from the next, and the row or series of pictures is in the form of a reflexed continuous spiral. In accordance with my invention a novel mechanical movement useful in many other relations is used

to move the plate step by step and in a manner which brings the pictures into position one after another and always in the same order. In the preferred arrangement the plate is rotated step by step, first in one direction and then in the other about a pivot or axis that is automatically moved back and forth along a line parallel to the surface of the plate, so that the plate has a movement of rotation combined with a bodily movement transverse to its axis of rotation.

I prefer to drive the mechanism by some suitable motor, such as a governor controlled spring motor, which will drive at substantially constant speed, even though the operator be unskilled. By using overlapping blades which move in opposite directions I secure an improved shutter having a maximum speed of closing and opening. To permit daylight loading I provide a suitable plate holder which can be inserted and removed at will, and can be controlled from the exterior of the camera to expose or cover the sensitive plate, as desired.

My invention will best be understood in connection with the accompanying drawings, in which merely for purposes of illustration I have shown one of the many different forms in which my invention may be embodied, and in which Figure 1 is a front view of one form of apparatus embodying my invention; Fig. 2 is a rear view of the apparatus shown in Fig. 1; Fig. 3 is a longitudinal horizontal section along the line 3—3 of Fig. 2; Fig. 4 is a longitudinal vertical section along the line 4—4 of Fig. 3 with part broken away to show details of the spring motor and looking at the front of the driven wheel; Fig. 5 is a vertical longitudinal section along the line 5—5 of Fig. 3 and looking at the rear of the driven wheel; Fig. 6 is a plan view of the negative; Fig. 7 is a plan view of the improved picture vehicle or glass plate; Fig. 8 is a plan view of the holder for the picture vehicle; Figs. 9 and 10 details of the holder; Fig. 11 is a view in elevation of the shutter looking from the interior of the camera toward the front. Fig. 12 is a plan view of the shutter blade; Fig. 13 a vertical longitudinal section on the line 13—13 of Fig. 1 showing details of the driving mechanism for the shutter and the other parts of the device, and showing the lens tube in elevation; Fig. 14 a section on the line 14—14 of Fig. 13; Fig. 15 an end view of the head.

shown in Fig. 13; Fig. 16 a transverse section of the parts 94 and 95 of Fig. 13; Fig. 17 a section of the gear 91 of Fig. 13, showing the pin clutch; Fig. 18 a rear view of the apparatus with a cover on the back removed to show the motor and gearing; Fig. 19 a longitudinal vertical section through the center of the driven wheel 45 and showing the plate holder in section and with the sensitive plate in position to be exposed; Fig. 20 a longitudinal section along the line 20—20 of Fig. 2; Fig. 21 a vertical section along the line 21—21 of Fig. 1 and the axis of the lens showing the parts in position for use as a camera; Fig. 22 a plan view of the front of the plate holder; Fig. 23 a section along the line 23—23 of Fig. 22; Fig. 24 a detail of the holder shown in Fig. 22; Fig. 25 a section along the line 25—25 of Fig. 22; Fig. 26 a front view of the cover of the plate holder in the closed position with most of the rim 108 removed and certain parts broken away; Fig. 27 a front view of the same plate holder with the cover open; Figs. 28 and 29 plan and end views of one of the vanes or leaves of the cover of the plate holder; and Fig. 30 a vertical section showing on an enlarged scale the inner and outer ends of my improved spring for the motor.

In the device which I have shown merely as an illustration of one form in which my invention may be embodied, I provide a frame strong enough to support the other parts of the apparatus and preferably made in the form of a light-tight box 40 which may be used as a camera. Some part of this frame or box, preferably the front 41, is movably mounted or hinged to form a door which permits easy access to the interior of the box at will, and is normally held closed by a suitable catch. In the particular arrangement shown, an extension frame 42 is secured to the back of the box 40 to support part of the driving mechanism. A carrying handle 43 and a finder 44 facilitate the use of the apparatus.

In order to give the desired motion to the picture vehicle or picture bearing element which is used when pictures are projected and to the sensitive plate which is used when pictures are being taken, I provide a movable carrier on which the picture vehicle or sensitive plate can be mounted when in use. This carrier is driven by a novel mechanical movement which may be used in many other relations and for other purposes than that shown and which I claim broadly as my invention. The carrier rotates about an axis which is automatically moved in a direction parallel to the plane of rotation of the carrier while the carrier is rotating. The preferred embodiment of my invention is that shown in the drawings, in which, as best shown in Figs.

3, 4, and 5, a rotatable carrier in the form of a driven wheel 45 is rotatably mounted on a carriage 46, which is slidably mounted in some suitable way, as, for example, on a slideway 47, so that it can move in a plane 70 parallel to the plane of rotation of the carrier and at right angles to its axis of rotation. The carrier may be rotatably mounted on the carriage in various ways, as for example on an axle 48 fixed to the 75 carriage.

The carrier or driven wheel 45 may be rotated and the carriage 46 simultaneously moved back and forth in various ways, but I prefer to accomplish this result by the 80 novel mechanism shown in the drawings. I provide a driving pinion 49 which is journaled in the frame 40 and is driven in any desired manner. At one end of the pinion the teeth are cut away to leave on the pinion 85 a circular portion 50.

In the particular form of device shown the pinion is tubular, as shown in Figs. 5 and 13, but this construction is merely to permit the apparatus to be used as a projector. For 90 the many other purposes for which the mechanical movement is useful the pinion and the shaft on which it is mounted may be made solid. The driving pinion drives the driven wheel which rotates on the axle 48 95 and comprises a series of teeth or pins 51, best shown in Figs. 3, 4, and 5, and in mesh with the driving pinion. The teeth or pins 51, are so arranged, that some of them are nearer the axis of rotation of the driven 100 wheel than others, and as a result the driving pinion and driven wheel are always in mesh, even though the axle 48 of the driven wheel is moved toward and away from the driving pinion. I prefer to arrange the 105 teeth or pins 51, as best shown in Fig. 5, in a regular row or series, in which all pins are at the same distance from each other, and the row or series is in the form of a spiral, 110 so that every pin is at a different distance from the axis of rotation. The driven wheel may for many purposes be made solid, but in the particular construction shown is cut away at certain points so as to form wide slots which permit light to pass 115 through the wheel. In the preferred construction the wheel is cut away so as to have a spiral rib 52 on which the pins are mounted, and crossbars 53 for holding and steady- 120 ing the spiral rib. The intermediate parts are cut out to leave wide slots between the 125 rib 52 and the various crossbars 53.

When the pinion 49 engages one side of the spiral row of teeth or pins 51 its rotation will cause the driven wheel to rotate in one 125 direction and at the same time move bodily toward one end of the slideway 47, but when the pinion, although still rotating in the same direction, engages the opposite side of the row of teeth the driven wheel will rotate 130

in the reverse direction and at the same time move bodily toward the other end of the slideway.

It will be noted that when the teeth 51 are uniformly spaced every revolution of the driving pinion 49 causes the same linear movement of that part of the driven wheel in alignment with the pinion, irrespective of whether the pinion is near the outer end or the inner end of the series of pins. The angular movement of the driven wheel due to one revolution of the pinion is much greater when the pinion is near the inner end of the row of pins than when it is near the outer end, but the linear movement is always the same. This feature is of great importance, because it enables me to place the maximum number of pictures on the picture vehicle or plate carried by the driven wheel 45 and to reduce the space between pictures to a minimum by arranging the pictures in a spiral row in which the linear distance between each picture and the next in the series is always the same. If the picture carrier were always turned through the same angle to shift from one picture to the next of the series the linear distance between two successive pictures near the rim of the carrier is much greater than the linear distance between two corresponding pictures near the center, and therefore much of the plate surface near the rim is wasted.

In order to insure that the pins or teeth 51 will always be in proper engagement with the driving pinion I provide means for maintaining the teeth and pinion in mesh in every position of the driven wheel 45. I prefer to provide yielding means for resiliently holding said teeth and pinion in engagement, and the preferred construction is that best shown in Figs. 3 and 4, in which resiliently mounted control members, such as the control wheels 54, act upon the driven wheel 45, preferably by engaging the edge of the spiral rib 52, which is channeled or grooved to cooperate with the sharp edges of the control wheel. Any other desired means may be used to maintain a pressure tending to keep the pinion and teeth in engagement.

As clearly shown in Fig. 21, these control wheels are mounted on slides 55 which slide in slideways 56 and carry journals 57 for the axles of the control wheels. The control wheels are resiliently held in engagement with the spiral rib by some suitable means, such as springs 58 connected by cords or flexible couplings to the slides 55. The control wheels are preferably mounted near each other in such relation that one tends to move the driven wheel 45 along the slideway 48 in one direction, while the other tends to move it in the opposite direction. The slides 55 keep the control wheels in engagement with the spiral rib 52 in all po-

sitions of the carrier, while the springs 58 cause the pinion to engage the pins very firmly yet yieldingly, especially as the pinion approaches the last pin at either end of the series. The driving pinion 49 always rotates in the same direction, and the driven wheel rotates in one direction until the last pin reaches the pinion, whereupon the last pin is carried around by the pinion until the pinion is on the other side of the row of pins. During this shift or transfer the position of the driving pinion does not change, but the driven wheel changes its relation to the pinion. I may in some cases place a stationary guide near the pinion with just sufficient clearance to permit a pin 51 to pass between the guide and pinion as long as the pin is between the teeth of the pinion. This is a precaution to prevent the pin getting out of mesh with the pinion, and need not be used in most cases. The continued rotation of the pinion then rotates the driven wheel in the reverse direction until the last pin at the other end of the row reaches the pinion and is carried around by it, whereupon the driven wheel again reverses and rotates as in the first instance, and so on. To facilitate this shift or change as the last pin goes around the pinion, I provide suitable shifting means for exerting a pressure which will assist the action.

The preferred construction comprises transfer members 59, best shown in Fig. 5, mounted on the carrier 45 and preferably in the form of plates having a thickness less than the cut-away portion of the teeth of the pinion, so that the transfer members directly engage the circular portion of the pinion. This portion is virtually a pin or stop cooperating with the transfer members, which have a cam surface for engaging this portion of the driving pinion and compelling the driven wheel to shift so as to bring the pins from one side of the driving pinion to the other.

In many cases the purpose for which my novel mechanical movement is useful will permit the pinion 49 to be driven continuously, but in the present device, where it is necessary to hold the picture vehicle stationary while each picture is being exhibited and then to move the vehicle far enough to bring the next picture into position, the pinion 49 is driven by any suitable driving means, such as an intermittent gear which will impart to it a step-by-step rotation. It may be driven directly by hand, if desired, but I prefer to make its operation practically automatic and its speed practically independent of the skill of the operator by driving by some motor mechanism, such as a spring motor, which need be wound only at intervals. The details of the motor and connections which I prefer will be more fully hereinafter described.

In order that the operator may know at all times the exact position of the driven wheel 45 I provide a suitable indicator. In the preferred construction the indicator 5 comprises a pointer or index 60 extending through the wall of the box 40 and with its inner end actuated by the carriage 46, so that it moves back and forth with the carriage. The position of the carriage is dependent upon the position of the driven wheel and by noting the position of the indicator the operator knows the exact point 10 which the driven wheel has attained in its cycle of movement.

With the apparatus constructed as above described the picture vehicle or picture bearing element has the pictures arranged on it as shown in Fig. 7, in the form of two spirals, one within the other, and with their 20 ends joined. By varying the arrangement of the teeth on the driven wheel the arrangement of the pictures on the picture vehicle can be correspondingly varied as desired. The picture vehicle is of some noninflammable transparent material, such as glass, and is preferably in the form of a thin plate 61, conveniently made octagonal, although the shape is immaterial. The picture vehicle is held by a suitable holder, such as the annular holder 62 shown in Figs. 8, 9 and 10. This holder has clamping means for the plate, such as fixed studs 63, and an adjustable clamping stud 64 to engage the edges of the plate and hold 30 it firmly in position. The holder is detachably secured to the driven wheel 45 in any suitable way, preferably by means of two fastening pins 65 which are secured to the holder and enter sockets 66 on the driven wheel. I also in some cases provide steady- 40 ing pins 67 about halfway between the fastening pins 65 for insuring that the holder remains substantially parallel to the driven wheel.

When the plate 61 is mounted on the driven wheel, as best shown in Fig. 8, the pictures are in front of the cutaway portions or slots of the wheel. As the mechanism operates, each picture in turn comes in front of the tubular driving pinion 49, stops, and then moves on to make room for the next. To project light from any suitable source through the tubular pinion and through the picture vehicle, I provide in alignment with the tubular pinion and in the back wall of the box 40 an opening normally closed by a cap 68 which is removed when the device is used as a projector. The light is focused to enter the tubular pinion, 50 pass through the slots in the driven wheel, through the pictures on the plate carried by the wheel and on through the lens. The machine is operated, and each picture is automatically brought into position, held 60 stationary while the shutter is opened and

closed, the picture vehicle then shifted while the shutter is closed to bring the next picture into position, and so on.

Owing to the novel arrangement of the series of pictures to form a closed figure of 70 which some parts are nearer the center of rotation of the plate than others, all the pictures on the picture vehicle or plate 61 can be exhibited over and over again merely by continuing the movement of the plate. For 75 example, starting at the picture A, Fig. 7, the plate is automatically moved in a counter clockwise direction so that the pictures spaced equidistantly to form the series from A to B, some in this series being at a 80 different distance from the center of the plate than others, appear one after the other, in front of the tubular pinion. While the inner end pin is going around the tubular driving pinion 49 the pictures C, D and 85 E are brought into position one after the other in front of the pinion and illuminated. When the inner end pin is in position to bring picture B in front of the pinion the relation of the pins 51 and the driving pinion is such that rotation of the pinion in the same direction as before causes the reverse rotation of the driven wheel 45 in a clockwise direction and brings the series of pictures E to F into position, until as the 90 outer end pin goes around the driving pinion, the pictures G, H and I are brought successively into position, until finally the plate 61 is back to its initial position. If desired the exhibition can be repeated at 95 once and without any changes or adjustments, by merely continuing the normal movement of the mechanism to cause the plate 61 to repeat its movements.

The utility of moving picture apparatus 105 depends to a large extent upon the efficiency of the shutter, and in accordance with my invention I provide a very simple and substantial shutter which is exceedingly quick acting, and in which the speed of operation 110 both in closing and opening is twice the speed of movement of the leaves composing the shutter. Owing to its rapidity of action my improved shutter is of great utility in all kinds of cameras and photographic devices generally, and is not limited to the particular apparatus here shown. My improved shutter comprises, as best shown in Figs. 11 and 12, two overlapping relatively movable blades 69, preferably made of thin 115 black, hard rubber, and perforated in such a way that in one relative position of the blades the perforations 70 are in register but in another position the perforations are out of register and no light can pass. The perforations 70 may be of any desired shape or outline, but are preferably circular. When the shutter is partially open the opening through it is lens shaped, due to the overlap 120 of the two circles, but when it is fully open 125

the opening through it is a circle. It is evident that the shutter opens from the center of the circle and closes toward the center. These blades are preferably mounted on pivots 71 intermediate their ends, so as to move toward and away from each other, like the blades of a pair of shears, and are actuated by some means which will give them a quick motion. In the preferred construction a spring 72 holds the blades against an actuating cam 73, preferably square in outline. When the blades are against the flat sides of the cam, as shown in Fig. 7, the perforations 70 are out of register and the shutter is closed, but as the cam turns through one quarter of a revolution the blades 69 first swing away from each other until when the parts are as shown in Fig. 5 and the corners of the cam 73 engage the shutter blades, the openings 70 come into register, and then swing back to the closed position as the blades again engage the flat sides of the cam. The mechanism described gives a very quick movement to the shutter blades, yet the speed at which the shutter is opened and closed is twice that at which the shutter blade moves, and is the maximum that can be obtained from a shutter using moving blades. This very desirable result is due to the fact that the two overlapping blades move in diametrically opposite directions, and therefore their speed relatively to each other is a maximum, and twice the absolute speed of either one.

In the particular construction shown the shutter cam 73 has a tubular hub and is mounted on the door 41 in some suitable way, as for example in a journal 74 in which it is held by a collar 75 secured to the outer end of the hub of the cam. Since the door must be opened and closed some form of detachable coupling is necessary to permit the cam to swing away from the driving mechanism as the door is opened and to be reconnected in proper relation to the remainder of the mechanism as the door is closed. For this purpose, as appears from Figs. 11 and 18, I provide the inner end of the cam hub with recesses or notches 76 for receiving co-operating members, such as a pin 77 yieldingly mounted to automatically engage these recesses or notches as the door is closed and then properly couple the cam to the driving mechanism. I prefer to mount the pin 77 in a head 78 which is splined on the end of the shutter driving shaft 79 and is yieldingly held by a spring 80 in such a position that its tapering end will enter the tubular cam 73 as the door is closed. As soon as the cam is in the proper angular relation to the shaft the pin 77 snaps into the recesses and couples the shafts to each other in that angular relation.

65 In the apparatus illustrated the shutter

blades are mounted on the door 41 to swing between the picture vehicle and the lens. As shown more in detail in Fig. 21, the lens is mounted on the front 41 of the camera in a lens tube 81 threaded into an adjustable holder 82 which is slidably mounted in a tubular guide 83, and may be moved back and forth at will by some suitable means, such as a pinion in mesh with rack teeth on the holder 81. A knurled head 84 connected to the pinion enables the operator to make this adjustment very easily and quickly. A lens cap 85 is provided to cover the lens when the camera is not in use.

It is necessary that the shutter and the picture vehicle or glass plate 61 move in synchronism and in such relation that the shutter is open only when the plate 61 is standing still, and is closed while the plate is moving. This proper relative movement may be obtained by various forms of interlocks between the plate mechanism and the shutter, but the preferred form of mechanism is that shown, in which the shutter driving shaft 79 and the shutter cam 73 are given a step by step rotation by a suitable means such as an intermittent gear 86, so proportioned that each time a pin of the gear engages a slot in the slotted wheel the cam is quickly rotated one quarter of a revolution, and is then held stationary until a pin again engages a slot. The pin 77 of the coupling is always in the same angular relation to the slotted wheel of the intermittent gear, and consequently the shutter cam 73 is always coupled to the shaft 79 with its flat sides in the same angular relation to the intermittent gear. As the shutter cam turns the shutter blades 69 approach each other, and the perforations 70 begin to overlap. The shutter is fully open when the cam has made a one-eighth turn and its diagonally opposite corners engage the blades 69, as shown in Fig. 5. As the cam continues to turn the shutter begins to close until the cam completes one-fourth of a revolution and its flat sides are engaged by the blades 69, whereupon the pin on the intermittent gear leaves the slot and the cam is locked until the next quarter revolution.

In order to interlock the shutter and the driven wheel 45 which carries the picture vehicle and compel them to move in proper sequence I connect the intermittent gear 86 through a countershaft 87 to a second intermittent gear 88, which is geared to and drives the driving pinion 49 with a step by step movement. The intermittent gears 86 and 88 are so set with relation to each other, as shown in Fig. 13, that they operate the pinion 49 and the cam 73 alternately. While the pin of either gear is driving the slotted wheel of that gear the other gear is inactive, as its pin is out of the slot and its slotted wheel is held stationary. This setting of the

gears not only causes them to operate alternately and insures that the driven wheel 45 and the shutter cam 78 operate in proper relation, but it also equalizes the load on the driving motor.

The intermittent gear 88 may drive the driving pinion 49 in various ways, but I prefer to provide means by which the driving pinion can be started and stopped at will without stopping the intermittent gear. In the preferred arrangement as best shown in Fig. 13, the slotted member of the intermittent gear 88 is secured to a tubular shaft 89 containing a slideable clutch member 90 which can be slid into and out of clutching relation to a pinion 91 which is in mesh with a gear 92 on the tubular shaft or extension of the driving pinion 49. I prefer to support the outer end of this tubular shaft 20 in a journal 93.

In order to take up wear in the intermittent gear I provided novel adjusting means, comprising a journal 94 for the shaft 80. This journal is eccentrically mounted in a collar 95 on the extension frame 42. By rotating the eccentric journal the slotted wheel of the intermittent gear can be moved toward and away from the other wheel.

In order to render the speed of the mechanism substantially constant regardless of the skill of the operator, I prefer to drive it from some form of motor such as a spring motor which may be wound while the mechanism is running. I prefer, as shown in Fig. 18, to connect the countershaft 87 through a suitable train of gears to the spring barrel 96 of a spring motor so constructed that it may be wound at will by means of a winding shaft 97.

In order to control the speed of the mechanism and also to steady its rotation, I provide suitable control and steadyng means, such as a flyball governor with weights 98 much heavier than necessary for a mere governor and heavy enough to have a very considerable fly wheel effect. The shaft of the governor is geared to the countershaft 87 and I have found it most advantageous to have this gearing so proportioned that the 50 governor shaft makes four revolutions to one revolution of the countershaft. The governor has a friction disk 99 which engages an adjustable brake 100 by means of which the speed can be controlled, and also cooperates with a movable stop 101 which can be manipulated to start and stop the mechanism.

When the device is used as a moving picture camera a sensitive film or photographic plate is mounted on the driven wheel 45 and exposed while the mechanism is running, so that a negative is made with the pictures arranged on it as shown in Fig. 6.

Since a large number of pictures are made 65 on the plate close to one another and in

rapid succession, I provide means to restrict the light to the desired portion of the plate during the taking of each picture. Various means may be used to prevent dispersion of the light and consequent fogging of the plate beyond the edges of each picture, but, as best shown in Fig. 21, I prefer to use an opaque barrier or vignette 102 to circumscribe the area which is lighted during the taking of each picture, and prevent leakage of light along the surface of the plate or film. This barrier or vignette 102 is preferably tubular, and may be round, square, oval, or any other shape desired. The barrier is yieldingly mounted with one end in light tight relation to the plate and the other end in position to permit light to pass from the lens to the plate. This tubular barrier may, for example, be telescoped into a socket 103 on the inner side of the door 41, and may be yieldingly held in such position as to prevent escape of light along the sensitive plate by springs 104. When the inner end of the barrier 102 is in light tight relation to the sensitive plate the definite and circumscribed area within the inner end of the barrier may be very strongly lighted without affecting adjoining portions of the plate.

The tubular barrier should be pulled back 95 out of the way when the plate holder is about to be opened or closed, or when the picture vehicle is to be placed in position, and therefore I provide means, such as a fork 105, which is mounted to rotate into 100 and out of position to engage the barrier and also to move in a direction to pull the tubular barrier toward the door 41 against the thrust of the springs. In the preferred construction the fork is secured to a control 105 rod slidably and rotatably mounted in the door 41 and provided with a head 106 for easy manipulation.

The tubular barrier 102 is useful, not only to prevent fogging the plate, but also in giving the projected picture any desired outline. For this purpose the barrier is released until its inner end is in contact with the picture vehicle or glass plate 61, which is mounted in the holder in such a way that the end of the barrier engages the uncoated side of the plate and therefore does not mar the emulsion coating on the plate.

In order to produce the desired series of pictures a photographic plate is carried across the inner end of the tubular barrier 102 with an intermittent motion of such a character that the desired series of pictures is produced on the plate. In accordance with my invention I make a moving picture camera that can be loaded in daylight with a flat plate, instead of a flexible film, and I consider this feature to be broadly new. This plate may be of any suitable kind, such as the ordinary glass photographic plate,

but I prefer to use a sensitized plate 107 of celluloid, circular in form, and with a hole in the center, as shown in Fig. 6. The plate is exposed in a novel holder which is suitable for mounting on the driven wheel 45. As best shown in Figs. 22 and 23, this plate holder comprises a rim 108, provided with gear teeth on the outer edge and an inwardly projecting flange on the inner edge with radial slots 109. The holder has a back 110 preferably cupped out or recessed to receive the sensitive plate, and perforated at the center to receive a spool 111, which projects through the back 110 and carries a loose clamping ring 112 for clamping the sensitive plate 107 to the back 110, and a lock nut 113 threaded on the spool for pressing the clamping ring against the plate. The clamping ring and lock nut are shaped to form an annular groove 114 at their edges above the surface of the sensitive plate in the plate holder.

To enable the operator to load the plate holder, place it in the camera in daylight, expose the plate at will, and remove the plate holder with the exposed plate from the camera in daylight. I provide on the plate holder a light tight cover which can at will be thrown back to expose the plate and returned to cover the plate without opening the camera. In the preferred construction I provide a cover which is operated by relative movement of the back 110 and the rim 108 of the plate holder. To permit this relative movement I attach the back 110 to the rim by studs 115 threaded into the rim and provided with shoulders which leave between the head of the stud and the rim 108 a space sufficient to receive the edge of the back 110, while to limit this relative movement lugs 116 on the edge of the back 110 engage the studs 115. To hold the parts against accidental displacement yet permit intentional movement, an impulsive or yielding stop, such as a spring 117, is mounted in position to engage one of the studs 115.

The form of cover which I prefer for the plate holder is a novel form of iris diaphragm which is of general utility and is not restricted to the particular device shown. This diaphragm or cover, shown in the open position in Fig. 26 and in the closed position in Fig. 27, is operated by relative movement of the rim 108 and back 110. The cover is made up of a number of overlapping arc shaped vanes or leaves, each having a length of about one-fourth of the circumference of the rim 108. In the closed position the vanes overlap and have their inner edges in the groove 114, so there is no leakage of light at the center, as with the usual type of iris diaphragm. The vanes are preferably made of black hard rubber, which is light and rigid, and is opaque to all rays that

affect the sensitive plate. As shown in Fig. 29, each vane is provided at one end with a pin 118 on one side and at the other end with a pin 119 on the other side. When the diaphragm is assembled each vane will have one end slidably connected to the rim 108 by the pin 118 which extends into one of the radial slots 109 in the flange on the rim 108, and its other end pivotally connected to the back 110 near the edge by the pin 119 which enters a hole 120 on the back 110. For example, as shown in Fig. 26, the two adjacent vanes 121 and 122 are slidably connected to the rim 108 by their pins 118 which enter slots 109 in the rim 108, while at the other end they are pivoted to the back 110 by their pins 119. The pivoted end of each vane is overlaid by the slidably connected end of another vane. For example, the pivotally connected end of vane 122 is overlaid by the slidably connected end of another vane 123, which is shown broken away in Fig. 26 to show the pivoted end of vane 121. The pivoted end of the vane 124 is overlaid by the slidably connected end of another vane 125, and so on. Relative rotation of the rim 108 and back 110 from the relative position of Fig. 26 to that shown in Fig. 27, or about one-fourth of a turn, moves all the vanes from closed position to the open position. When the diaphragm is open, as shown in Fig. 27, the vanes lie one above the other, one end of each vane projecting a slight distance beyond the corresponding end of the vane immediately above it, as shown by the vanes 121 and 122.

The plate holder is loaded in the dark room by placing the sensitive plate or film against the back 110 with the hole in the film in registry with the hole in the center of the back. The spool 111 is then slipped through the back 110 and the film, the clamping ring 112 slipped over the end of the spool into contact with the film, and the lock nut 113 screwed on the spool until the spool, film, and clamping ring are all firmly clamped to the back 110. The cover is closed, and the plate holder is ready to be placed in the camera.

The plate holder is detachably secured to the driven wheel 45 in any suitable manner, preferably by fastening pins 126 similar to the pins 65 used on the holder 62 for the picture vehicle or picture bearing element and also by a set screw 127, best shown in Fig. 19, for clamping the spool 111 to the driven wheel 45 with the end of the spool fitting snugly a projection on the hub of the driven wheel. This projection both centers and steadies the plate holder, and is preferably made as shown to fit into the central opening of the spool 111.

In order to control the cover or iris diaphragm while the plate holder is in the camera I provide light tight actuating means 130

for at will rotating the rim 108 with relation to the back 110. The preferred means, as shown in Figs. 19 and 20, comprises a pinion 128 mounted inside the camera 40 on a shaft 129 which projects through the wall of the camera and can be turned at will. The shaft 129 is mounted in a bearing 130 which extends into an arc shaped slot in the wall of the camera. The bearing 130 is provided with a shoulder sliding along the inner wall of the box. A slide 131 long enough to cover the slot in every position of the bearing 130 is attached to the bearing and moves with it, as shown in Fig. 20. The edges of the slide 131 are overlapped by guides 132. A clamping head 133 is threaded on the bearing which is slightly flattened where it passes through the slide to prevent turning of the bearing when the clamping head is tightened. The clamping head enables the operator to clamp the bearing and slide very firmly to the wall of the box at any desired point of the slot. The pinion 128 may be moved along the slot into and out of mesh with the teeth on the rim 108 at will and the bearing 130 clamped solidly to the side of the camera while the cover of the plate holder is being operated.

Although the apparatus can be driven by any desired form of spring motor, I prefer to use a motor illustrated in the drawings and embodying a spring constructed in a novel manner and in accordance with my invention. The construction of this spring is best shown in Fig. 30, which is a transverse section through the spring barrel of the motor and shows a part of the arbor with the end of the spring attached to it, and part of the intermediate portion of the spring and the outer end of the spring where it is attached to the spring barrel. As clearly shown in this figure, the spring barrel 96 is connected to the arbor 134 by a spiral spring made up of a spiral leaf 135 connected at one end to the barrel and at the other end to the arbor. This spiral spring is reinforced by placing inside of it one or more auxiliary leaves 136, preferably of substantially the same thickness as the leaf 135 and lying inside the first spiral in a position to reinforce it. The auxiliary leaf 136 is not connected either to the spring barrel or to the arbor, but is connected to the leaf 135 by some kind of a connection which will permit the leaves to move over each other longitudinally but will prevent lateral displacement. The leaves may, for example, be held in proper relation by a lost motion connection, as for example, a rivet 137 secured to one of the leaves, such as the leaf 135, and extending loosely through a slot 138 in the other leaf so as to permit considerable longitudinal displacement of the leaves, but prevent lateral displacement. As many auxiliary leaves as desired may be used and all connected together in the same

way. By this arrangement I obtain a spring which is flexible as a thin spiral spring like the leaf 135, but which has more power and sustained driving force.

The pictures on the sensitive plate may be arranged in any desired way by moving the plate in a suitable manner, but I prefer to arrange the pictures at differing distances from the center of rotation of the plate and in a series which forms a closed figure, such as the closed reflex spiral shown in Fig. 6. If the pictures are arranged in this manner they can be shown over and over again without stopping the projector, and the closed reflex spiral is preferred, because it utilizes practically all of the surface of the plate. Another marked advantage is that the greater part of the movement of the plate holder is a movement of rotation about a center, and is therefore much more regular and uniform than is possible if the plate holder is moved in an irregular path containing sharp angles and sudden change of direction.

When a picture is to be taken the loaded plate holder is inserted in the camera by opening the door 41 and clamping the plate holder to the carrier 45. The door is then closed, the control pinion moved into mesh with the teeth on the rim 108 of the plate holder, the tubular barrier held back out of the way, and the rim 108 rotated to swing the vanes of the cover back into the open position. This uncovers the plate. The tubular barrier is then let down into light tight relation with the plate, and all is ready for exposure. With the cap on the lens, the motor is wound up, the governor released, and the mechanism begins to run, driving the shutter only. The clutch between the driving mechanism and the pinion 49 is thrown in, and at the same time the cap is removed from the lens. As the pinion 49 is moved step by step the driven wheel 45 begins to rotate, the shutter opening and closing at the proper times. The plate holder carries the plate step by step across the inner end of the tubular barrier 101 and a series of pictures are taken, as shown in Fig. 6. The operator notes the position of the indicator 60 when he takes the cap off the lens. The indicator swings in one direction and then in the other as the carriage 46 moves back and forth, and when it returns to its initial position the series of pictures is completed. The cap is put back in the lens and the mechanism stopped. The tubular barrier is drawn back, the cover of the plate holder closed by means of the control pinion, the door 41 opened, and the plate holder containing the exposed plate removed.

My invention may be embodied in many other forms than that shown and described, and I therefore do not wish to be restricted

to the device disclosed, but intend to cover all changes and modifications within the spirit of my invention and the scope of the appended claims.

5. What I claim and desire to secure by Letters Patent of the United States is:

1. In a moving picture apparatus, the combination of a movable carrier for a picture bearing element or a sensitive plate, 10 mechanism for moving said carrier step by step, a shutter, mechanism for intermittently moving said shutter, and means for interlocking said mechanisms to cause said carrier and said shutter to move alternately.

15. 2. In a moving picture apparatus, the combination of a movable carrier for a plate, an intermittent gear for moving said carrier step by step, a shutter operating mechanism, a second intermittent gear for actuating said 20 shutter mechanism, and means for driving and interlocking said intermittent gears to hold said shutter mechanism stationary while said carrier is moving and vice versa.

25. 3. A moving picture apparatus comprising a movable carrier, a shutter, mechanisms comprising a continuously rotating driving member and an intermittently actuated driven member for moving said carrier step by step and for actuating said shutter when 30 said carrier is stationary and a fly ball governor connected to said actuating means and comprising balls of sufficient mass to store up energy and exert a marked fly wheel effect and thereby steady the movement of 35 said mechanism.

4. A moving picture apparatus comprising mechanism having an intermittently actuated driven member for moving a picture vehicle step by step, a shutter, mechanism 40 having an intermittently actuated driven member which actuates said shutter when said picture vehicle is stationary and holds it stationary while said picture vehicle is moving, and a motor connected to said mechanisms to drive said driven members alternately and operate said picture vehicle and 45 said shutter at a substantially uniform rate.

5. Moving picture apparatus comprising a movable carrier, driving means comprising 50 an intermittent gear for imparting a step by step movement to said carrier, shutter mechanism, a second intermittent gear for actuating said shutter mechanism intermittently, a countershaft connecting said intermittent gears to drive their driven members alternately, and a combined regulating and 55 steadyng device geared to said countershaft.

6. Moving picture apparatus comprising a movable carrier for a picture vehicle, 60 shutter mechanism, driving mechanism comprising an intermittent gear for operating said carrier and a second intermittent gear for operating said shutter alternately with said carrier, a countershaft geared to both 65 of said intermittent gears to actuate them

alternately, and a fly ball governor having weights sufficient to exert a marked fly wheel effect geared to said countershaft to run at approximately four times the speed of said countershaft.

70

7. A combined moving picture camera and projector comprising a light-tight box, a movable carrier in said box for the picture vehicle or sensitive plate, shutter mechanism mounted on said box, driving mechanism for 75 operating said carrier and said shutter mechanism alternately and step by step, a spring motor capable of being wound while running and mounted on said box to actuate said driving mechanism, and means for 80 automatically controlling and steadyng the movement of said mechanism.

8. A combined moving picture camera and projector comprising a light-tight box, 85 a lens mounted in one wall of said box, a tubular driving pinion mounted in the other wall of said box in alinement with said lens, means for admitting or excluding light from the interior of said tubular pinion, and a movable carrier driven by said pinion and mounted to bring different parts of the picture vehicle in succession in front of said pinion when driven by said pinion.

9. A moving picture camera comprising 90 a light-tight box, a movable carrier having a central projection for centering the back of a plate holder comprising a relatively movable back, a rim, a cover operated by relative rotation of said back and rim, and means projecting through the wall of said 100 box adjacent said carrier for engaging the rim of the plate holder to rotate it relatively to the back and thereby operate the cover.

10. Moving picture apparatus comprising 105 a light-tight box, a movable carrier in said box for carrying a plate holder, and means operative from the exterior of said box and movable at will into and out of operative relation to the plate holder secured to said carrier.

110

11. A moving picture apparatus comprising a light-tight box, a movable carrier mounted in said box, a control pinion extending through the wall of said box and movable toward and away from said carrier, and clamping means for positioning said pinion and making a light-tight joint with said box in every position of said pinion.

115

12. A moving picture apparatus comprising 120 a movable carrier for a picture vehicle, a shutter, driving mechanism for imparting a step by step movement to said carrier and for opening and closing said shutter while said carrier is stationary, and means for at 125 will connecting or disconnecting said carrier and said driving mechanism while said mechanism is in motion.

13. A moving picture apparatus comprising 130 a box having a movable wall actuating

mechanism in said box for driving a picture vehicle step by step and comprising a driving shaft for the shutter mechanism, a shutter mounted on the movable wall of said box, and means controlled by the movement of said movable wall to automatically connect said shutter mechanism in proper relation to said actuating mechanism.

14. A moving picture apparatus comprising a box having a door, actuating mechanism for imparting a step by step movement to the picture vehicle in said box and comprising a shutter driving shaft mounted in said box, a shutter actuating cam mounted on said door, and a detachable coupling between said shaft and said shutter cam for automatically disconnecting said shutter cam from said shaft as the door is opened and reconnecting said shaft and shutter cam in proper angular relation as said door is closed.

15. A moving picture camera comprising a shutter driving shaft, a pin carrying member splined on the end of said shaft, a door movable toward and away from the end of said shaft, a shutter cam mounted on said door and having a notch to engage said pin as said door is closed and thereby connect said cam and shaft in definite and predetermined angular relation.

16. A daylight loading moving picture camera adapted to use plates and comprising actuating mechanism for moving a plate in the camera to expose it at a plurality of points in succession, and means for at will uncovering or covering a plate while in the camera and connected to said mechanism.

17. A daylight loading camera for making moving pictures on a plate comprising actuating mechanism for rotating a sensitized plate about a center, means for at will inserting and removing a plate to bring it into and out of operative relation to said mechanism without exposure to light, and means for at will covering or uncovering the plate while in the camera in operative relation to said mechanism.

18. A daylight loading moving picture camera comprising a carrier for moving the plate to expose different portions in succession, means for securing a plate holder with a removable cover to said carrier, and means for at will removing and restoring said cover while said holder is in the camera.

19. A moving picture machine comprising a carrier for a flat picture vehicle mounted to rotate and move laterally in the plane of rotation, and driving mechanism for rotating said member step by step and laterally moving it in one direction to a predetermined limit and comprising means for automatically reversing the rotation and lateral movement of said carrier to return it to initial position.

20. A moving picture machine comprising

a picture vehicle carrier mounted to rotate and to move laterally, and driving means for intermittently rotating said carrier step by step to a predetermined limit and comprising means for moving said carrier laterally a predetermined distance at said limit, and then rotating said carrier in the reverse direction to its initial position.

21. A moving picture machine comprising a box having a window in one wall, a tubular driving pinion mounted to extend through another wall in alignment with said window, a support extending at right angles to the axis of said pinion, a picture vehicle carrier rotatably mounted on said support to move longitudinally thereof and having pinion engaging teeth forming a spiral about the center of said support, and means whereby said pins are held in engagement with said pinion.

22. A moving picture machine comprising a box having a window in one wall, a picture vehicle carrier mounted in said box to rotate in front of said window and to move laterally and having a row of pins projecting from said carrier and forming a spiral about the center of said carrier, a driving pinion for engaging said row of pins on opposite sides; a pinion guide extending part way around the terminal pins of the row, and means acting upon said carrier to force its teeth into engagement with said pinion when said pinion is on either side of said row of teeth.

22. A moving picture machine comprising a light tight box having a window, a driving pinion in the box adjacent said window, a carriage mounted to slide transversely of the axis of said pinion and of the center line of said window, a picture vehicle carrier rotatably mounted on said carriage and having a spiral rib thereon and a series of pinion engaging teeth forming a spiral identical with said rib, control members mounted adjacent said pinion, to engage opposite sides of said rib, and means for yieldingly moving said control members in opposite directions parallel to the direction of movement of said carriage to maintain said teeth in mesh with said pinion.

24. A moving picture machine comprising a box having a window, a picture vehicle carrier mounted to be capable of movement in front of said window in two directions in the plane of movement, a driving pinion in said box, pinion engaging teeth connected to said carrier and set in a line in the form of the path to be described by said carrier, and means for maintaining said teeth in engagement with said pinion to cause said pinion to travel along one side of said line of teeth around the ends, back along the other side and around the other end to initial position and thereby drive said carrier to cause a point on its surface to describe a closed curve of the shape of said line of teeth.

25. A moving picture machine comprising a box having a window, a picture vehicle carrier mounted in the box to be capable of movement in front of said window in two directions in the plane of movement, and driving mechanism for imparting to said carrier sufficient movement in both said directions to drive said carrier through a definite path to a predetermined limit and at 5 said limit shifting said carrier and driving it in the reverse direction through a parallel path to the initial position and thereby cause a point on the surface of said carrier to describe a closed curve.
- 10 26. A moving picture machine comprising a light box having a window, a picture vehicle carrier mounted to move in front of said window in two directions at right angles to each other and means for moving 15 said carrier in both said directions to cause a point on its surface to describe a closed curve, the movement in one of said directions being intermittent.
- 20 27. A moving picture machine comprising a light tight box, a driving pinion in said box, a picture vehicle carrier mounted to rotate and to move its axis in a direction transverse to the axis of said pinion and having pinion engaging teeth in a series to 25 form a spiral, and a pivoted indicator with its shaft extending through the wall of said 30
- box and having one end moved back and forth by the transverse movement of the axis of said carrier.
28. A moving picture machine comprising a light tight box, a driving pinion inside the box, a carriage mounted in said box to slide transversely of the axis of said pinion, a picture vehicle carrier rotatably mounted on said carriage and having a series of equi-distant teeth arranged in a spiral about its axis, means for keeping said teeth in mesh with said pinion, and an indicator connected to said carriage to be moved thereby and extending through the wall of said box to an 40 exterior point.
29. Moving picture apparatus comprising a movable carrier, a shutter, intermittently acting mechanism for driving said carrier and said shutter alternately, so that when 45 one moves the other is at rest, and vice versa, and a speed governor and regulator connected to said mechanism and having sufficient flywheel effect to compel a substantially uniform movement of said mechanism. 50
- In witness whereof I have hereunto set my hand this 11th day of January, 1915.
- JOSEPH PODJEVIN.
